WILLIAM A. LAWTON, OF NEW YORK, N. Y.

Letters Patent No. 74,099, dated February 4, 1868.

IMPROVEMENT IN GAS-TORCHES.

The Schedule referred to in these Letters Patent and making part of the same.

TO ALL WHOM IT MAY CONCERN:

Be it known that I, WILLIAM A. LAWTON, of the city, county, and State of New York, have invented a new and improved Gas-Torch; and I do hereby declare that the following is a full, clear, and exact description thereof, which will enable those skilled in the art to make and use the same, reference being had to the accompanying drawings, forming part of this specification.

This invention relates to a new and improved method of constructing torches for the lighting of gas, whereby the alcohol or other fluid burned for that purpose is more economically expended. It consists of a tube to contain the alcohol or other fluid, packed tight at the top, and opening at the bottom into a pipe, upon the end of which is screwed a wick-receiver or tube, covered at the outer end with a cap, said tube or wick-receiver being of greater bore, or diameter than the tube to which the same is screwed, whereby the wick is packed so closely as to prevent the leaking of the fluid used. It consists, also, in said tube, in which the alcohol is contained, opening at the top into a tube, connected with the tube opening from the bottom of the same, at any convenient point in the same, whereby air is supplied to the top of said tube containing the alcohol or other fluid. In the accompanying plate of drawings—

Figure 1 represents a central vertical section of my invention.

Figure 2 is a side view of a portion of the same.

Similar letters of reference indicate corresponding parts.

A is the alcohol-tube; B is a cap on the same; C is a pole, to which the tube A is attached; D is the supply-tube; E is the air-tube; F is the wick-holder; G is a cap on the same; H is a wrench. The tube A is made of brass or other suitable metal, of the same form, and in like manner attached to a pole or handle, C, as the tubes of torches now commonly in use. Said tube A is provided, on the top of the same, with a cap, B, to which said cap is attached, by a rod, the wrench H, as shown, for the purpose of turning the stop-cocks in gas-burners. The cap A is provided with a screw-thread, by means of which it is screwed down into the tube A, said tube A being provided on the inside of the same, at the top, with a screw-thread, to receive the same, as shown in the drawing. Upon the top of the tube A, and between the same and the cap B, at any convenient place, is a suitable packing, so as that when the cap B is screwed down, said tube will be perfectly tight. Into one side of the tube A, at the bottom thereof, and communicating therewith, is a supply-tube, D. The supply-pipe D is made of brass or other suitable metal, of the inside diameter of one-quarter of an inch, or of any other diameter, and of any desired length, as of the length of six inches, to the outer end of which is attached a coupling, as shown, said coupling being provided, on the inside of the same, with a screw-thread, to receive the wick-tube F, said wick-tube F being provided with a screw-thread on the outside of the same, by means of which said wick-tube F is screwed into the coupling above mentioned. Said wick-tube F is provided, also, with a flange, near said screw-thread, by means of which the connection of the wick-tube F with the tube D is made tight, the object of said screw-thread being that the wick-tube F may at any time be taken off, when required. Said wick-tube F should be of a little greater inside diameter than the tube D, so that when connected with the tube D, the wick in the wick-tube F will be so compressed in the tube D as to form a packing, and prevent leaking. Upon the outer edge of the wick-tube F is a cap or cover, G, secured to the same by a screw-thread, in the ordinary way, so as to protect the wick, and prevent the evaporation of the alcohol from the same. Communicating with the top of the tube A, by one end, as shown, is an air-tube, E, said tube E communicating by the other end with the tube D, at any convenient point in the same, as shown, the object of the air-tube E being to supply air, through the tubes D and F, to the upper part of the tube A, to fill any vacuum which would otherwise be created by the consumption of the alcohol from said tube A, and which would stop the flow of the alcohol from the tube D by the pressure of the surrounding atmosphere. The descending fluid or alcohol does not completely fill the tube D, but partially only, as shown by the blue lines along the lower part of said tube, for the supply of air (or air and nitrogen combined, resulting from the partial combustion of the air) through the wick is not in sufficient quantity to permit the rapid flow of the fluid, whereby the air passes above the fluid, as shown by the red arrows. The operation is similar to that of gas-torches now commonly in use.

Constructed as above-described, it constitutes a safe and convenient gas-torch for the lighting of gas, the

advantages of which are, that while sufficient fuel is furnished to the wick in the tube F, in no position of the torch will any alcohol or other combustible fluid contained in the tube A be wasted, and that the short wick in the tube F, by removing said tube, can be easily taken out and replaced. The tube B may be permanently closed tight at the top, and a fuel-tube may be inserted in the side of the tube B, for feeding the same, as shown, when preferred.

I claim as new, and desire to secure by Letters Patent—

1. A gas-torch, for all the purposes for which gas-torches are used, composed of the tube A, and supply-tube D, and air-tube E, and an enlarged wick-tube F, substantially as shown and described, and for the purposes set forth.

2. The air-tube E, in combination with the tube A and the tube D, substantially as shown and described, and for the purposes set forth.

W. A. LAWTON.
